UNITED STATES PATENT OFFICE.

GEORGE W. LINDSEY AND HARRY W. RALEIGH, OF BALTIMORE, MARYLAND, ASSIGNEES OF ONE-THIRD TO ARTHUR J. PRITCHARD, OF SAME PLACE.

FIRE-ESCAPE.

SPECIFICATION forming part of Letters Patent No. 276,610, dated May 1, 1883.

Application filed January 24, 1883. (No model.)

To all whom it may concern:

Be it known that we, GEORGE W. LINDSEY and HARRY W. RALEIGH, citizens of the United States, residing at Baltimore, Maryland, have 5 invented certain new and useful Improvements in Fire-Escapes, of which the following is a specification, reference being had to the accompanying drawings, forming part hereof, in which—

10 Figure 1 is a view of the front of a house with our invention applied at the windows thereof. Fig. 2 is a view in side elevation of our device detached. Fig. 3 is a view of the attaching-iron embodied in our invention. 15 Fig. 4 is a view of a section of our invention on an enlarged scale, showing the manner of attaching the rings; and Fig. 5 is a view with a weight attached at the bottom.

Like letters of reference mark the same parts 20 in all the figures.

A is the attaching-iron, having a hook-point, a, a spring, b, and a sharp rear point, c.

B is a twisted or cable wire rope, to which are connected at intervals rings C, either by 25 tying on in the loop of an ordinary single knot, or in any other suitable manner.

D is a pear-shaped weight, attached to the end of the wire rope.

The device may be attached to any ordinary 30 piece of furniture and hung out of a window, thus furnishing a ready means of escape, and

one not liable to get out of order. If a chair is handy, the escape may be secured by snapping the hook a over one of its legs or rounds. If this is not feasible, the upper end of the rope 35 may be passed around a larger article of furniture and the hook a snapped into one of the rings C. In the event no furniture is available for this purpose, the point c may be driven into the window sill or frame, and if these 40 be of metal or stone said point may be driven into the floor. The weight serves to cause the wire rope to assume a perpendicular position, and is also advantageous if it is desired to throw the escape into a window. 45

Having thus fully described our invention, what we claim, and desire to secure by Letters Patent of the United States, is—

1. The fire-escape herein described, consisting of the attaching-iron A, having hook a, 50 spring b, and rear point, c, the wire rope B, having the rings C knotted therein, and the weight D, all arranged and combined in the manner set forth.

2. The attaching-iron A a b c, as set forth. 55

In witness whereof we have hereunto set our hands.

GEORGE W. LINDSEY.
HARRY W. RALEIGH.

In presence of—

S. BRASHEARS,
W. A. BERTRAM.
